UNITED STATES PATENT OFFICE

2,324,527

REFRIGERATING APPARATUS

Willard L. Morrison, Lake Forest, Ill.

Application August 14, 1939, Serial No. 289,940

6 Claims. (Cl. 62—89)

This invention relates to refrigerating apparatus and has for its object to provide a new and improved device of this description.

The invention has as a further object to provide a refrigerating apparatus having compartments which are at different temperatures, so that articles of food can be kept in one compartment at a low temperature and in another compartment at a higher temperature. The invention has as a further object to provide a refrigerating apparatus having compartments which are communicating, but which are at different temperatures, one compartment being at a low temperature and another compartment being at a higher temperature. The invention has as a further object to provide a refrigerating apparatus having a compartment with a partition therein which extends upwardly from the bottom, but not clear up to the top, with a cooling device in one compartment which primarily cools this compartment, the cold air passing over the partition into the other compartment.

The invention has as a further object to provide a refrigerating device which may also be used as a table.

The invention has as a further object to provide a refrigerating apparatus which can be easily defrosted by brushing the frost off of the cooling element and without warming it up. The invention has as a further object to provide a refrigerating apparatus which can be defrosted while the refrigerating chamber remains cold and without taking the articles of food out of the refrigerating chamber.

The invention has further objects which are more particularly pointed out in the accompanying description.

Referring now to the drawings, Fig. 1 is a view showing a device embodying one form of the invention:

Fig. 2 is an enlarged sectional view taken on line 2—2 of Fig. 1;

Fig. 3 is a sectional view taken on line 3—3 of Fig. 2;

Fig. 4 is a fragmentary sectional view showing the lefthand portion of Fig. 3 with some of the parts in a different position;

Fig. 5 is a side elevation of one end of one form of adjustable partition;

Fig. 6 is a sectional view taken on line 6—6 of Fig. 4;

Fig. 7 is a sectional view taken on line 7—7 of Fig. 4;

Fig. 8 is a sectional view taken on line 8—8 of Fig. 4;

Fig. 9 is a sectional view showing a modified construction;

Fig. 10 is a detailed view showing one method of movably supporting the cooling element;

Fig. 11 is a view of the upper lefthand corner of Fig. 4, showing the cooling element moved up to be entirely surrounded by warm air in the room; and

Fig. 12 is a view showing a modified means for permitting pivotal movement of the partition.

Like numerals refer to like parts throughout the several figures.

In Fig. 1 I have illustrated a construction where the refrigerating apparatus performs two functions, namely a refrigerator and a table, thus having the two devices occupying substantially the same space. It is of course evident that the device may be used simply as a refrigerator and that it may be made in many different forms, sizes and shapes.

In carrying out the invention I provide a refrigerating receptacle 1. In the construction shown in Figs. 1, 2 and 3 the refrigerating receptacle is closed at the bottom and on the four sides and is made of any suitable heat insulating construction. As herein shown, it is made of two sets of walls 2 and 3, one within the other, the space between the walls being filled with heat insulating material 4 of any suitable kind. This refrigerating receptacle is provided at the top with a suitable door or doors. I prefer to provide two doors 5 and 6 which are preferably transparent, although this is not essential. In the construction shown there are two doors, the door 5 being hinged at 7 and the door 6 being hinged at 8.

Within the refrigerating receptacle is a cooling element 9 which may be of any desired form. It may be one of the types of ordinary evaporators as now used, but I prefer to use a cooling element having flat, smooth upper and lower faces and particularly a cooling element described in my patent application Serial Number 285,130, filed July 18, 1939. This cooling element is held in position below the doors and preferably near the upper edge of the refrigerating receptacle. I prefer to have the cooling element movably connected in position so that it may be moved up or down and I also prefer to have it pivotally connected to its support, as at 10. When thus movably or pivotally supported, some means is provided at the outer end of the cooling element to support this outer end, and for purposes of illustration I have shown the

outer end of the cooling element supported by the flexible supporting members 11 which are connected to the cooling element, preferably at two opposed edges thereof. These flexible supporting members are also connected to some fixed part, such as the wall of the refrigerating receptacle, by the fastening devices 12. I prefer to have the flexible supporting members removably fastened in position, as by means of the hook 13 which can be easily and quickly unhooked. There are preferably two of these flexible supporting members, one at each edge of the cooling element.

The cooling element may be moved up and down in any desired manner and by any desired means. As herein shown, the part 10a in which the pivot 10 is mounted, projects through a slot 10b in the inner wall 3 and is provided with an enlargement 10c which engages the outer face of this wall. An adjustable member 10d, such as a nut, is placed on the inside of the wall so that when tightened up it will hold the cooling element in any desired position. A groove 10e is formed in the heat insulating material so as to permit the up and down movement of the parts.

The refrigerant may be supplied to the cooling element in any desired manner, but I prefer to supply it by means of flexible conduits 14 and 15. There is an expansion valve 16 connected with the supply conduit 14 and with the cooling element. By having these conduits 14 and 15 flexible, it will be seen that the cooling element may be moved to various positions without affecting these connections.

The refrigerant may be supplied to the cooling element from any desired source. In order to make the device a unitary structure, I prefer to provide means for supplying refrigerant which may be located in a compartment 17 and which may consist of the usual mechanism for this purpose, such as the compressor 18, condenser 19, collector 19a, motor 20 and fan 21. The fan blows air through the condenser 19 and there are openings 22 in the wall of the compartment through which the warm air from the condenser is discharged.

When the device is to be used as a table there are provided a series of table leaves 23. As many of these leaves as desired may be used. These leaves are preferably hinged leaves having movable supports 24 by means of which they may be held in their operative positions. When it is desirable, these supports may be moved to the position shown in Fig. 2 so that the leaves may be dropped down as shown on the righthand side of Fig. 1, so as to be out of the way.

Within the refrigerating receptacle is a partition which extends to some point near the upper edge of the receptacle. This partition is preferably adjustable vertically and laterally or horizontally. This partition is preferably located at some point between the innermost edge of the cooling element and the opposed wall of the refrigerating receptacle and may be adjusted to any position between these points. It may be adjusted so that a part of the cooling element projects beyond it if desired. As herein shown the partition is made up of the members 25 and 26 which are slidable with relation to each other to adjust them vertically and which may be held in any adjusted position by any suitable means. As herein shown there are loops 27 at the opposed edges of one of the members, as for example, the member 26, the member 25 working in these loops as shown in Fig. 7. There is preferably a tight

fit of the member 25 in the loops 27 so that the two members will stay in any position to which they are adjusted. Any other suitable means may be used for holding the members in any adjusted position. By this means the partition may be varied in height so as to bring the upper edge closer or farther away from the cooling element.

This partition as it were divides the refrigerating receptacle into two chambers 28 and 29 which are connected together at their upper ends. These chambers may be varied in size by moving the partition laterally toward and away from the cooling element 9 so as to increase the size of one chamber and decrease the size of the other chamber. Any suitable means may be provided for holding the partition in any of its adjusted positions. As herein shown the partition is provided at the top and bottom and the opposed ends with the spring members 30 which engage the opposed faces of the inner walls of the refrigerating receptacle. These spring members permit the partition to be moved laterally and they also act to hold the partition in any adjusted position.

The cooling element 9 when in use is preferably in a horizontal position and any material to be cooled may be placed on top of it. I have illustrated a series of ice cube trays 31 on top of the cooling element but it is of course evident that any other material which it is desired to freeze may be placed thereon.

The chamber 28 directly below the cooling element will be the colder chamber and the chamber 29 will be the warmer chamber. The chamber 29, for example, may be provided with a series of trays, 32, 32a, 32b, etc. These trays are preferably wire woven trays and are open at the top and one side. They may be supported in position in any desired manner and may be set one on top of the other if desired. I prefer to have some means for lifting them up so that the material in the lower trays will be easily accessible. In the construction shown, this result is secured by providing at the opposed ends of the trays the supports 33 which are connected to a member 33a on which the trays rest. Arms 34 are connected to the supports 33, as by means of the pins 35 and the slots 36. These arms are pivoted at 37 and are provided with the members 38. Springs 39 are connected to the member 38 and to some fixed part, as the wall of the refrigerating receptacle. These springs tend to lift the trays upwardly and make it easy for anyone desiring to get at the trays, to lift them up. The arms and supports 33 are shown in dotted lines in Fig. 3 in a partially lifted position with one of the doors open. By opening the other door, the trays can be lifted higher if desired, to secure access to the bottom tray. Lifter rods 35a may engage pins 35 to assist in lifting the trays.

In Fig. 9 I have shown a modified construction where the refrigerating receptacle is entirely enclosed at the bottom ends, sides and top, one of the sides being provided with a door 40. There is a cooling element 9 and a partition made up of the members 25 and 26 which extends across the receptacle and engages the opposite walls by means of the spring members 30, the two members 25 and 26 being adjustable vertically. The air cooled by the cooling element 9 drops by gravity into the chamber 41 and the warmer air passes over the partition and drops by gravity into the chamber 42 so that the chamber 42 is cool, but at a higher temperature than the chamber 41. In this construction I have shown the compressor, motor and other refrigerating de-

vices in a chamber 43 which extends only part way across the refrigerating receptacle so that the section 44 of the bottom is higher than the section 45, although the bottom may be all of the same height if desired.

It will be noted that there is here a door in the side of the receptacle opening into one of the chambers so that access thereto can be secured, to remove material therefrom or place material therein without the cold air from the other chamber flowing out. It will further be seen that by opening this door the material may be removed from or inserted in the chamber 41 without the cool air passing therefrom. This may be facilitated by moving the partition to an inclined position as shown in dotted lines, the spring members 30 holding it in this position.

I prefer to provide a door 40a at the top of the refrigerating receptacle so that access can be had to the cooling element 9 and so that the cooling element can be moved up out of the receptacle, as is shown in the other drawings, for purposes of defrosting or for other purposes. This cooling receptacle may be constructed and mounted so that this can be accomplished by the construction shown in the other drawings.

In this construction I prefer to have the lower end of the partition pivotally connected in position so that it may be moved to an inclined position, not only to secure access to the chamber 41, but to reduce the height of the partition. For this purpose a construction similar to that shown in Fig. 12 may be used, where there is at each end a pin 46 which passes through a part 47 separate from the partition or part 25 and which also passes through a part 48 connected with the partition. There is a spring 49 surrounding the pin 46. The pins 46 act as pivots about which the partition can be moved and the springs 49 press the parts 47 against the parts 48 so as to hold the partition in any of its various positions.

The use and operation of my invention are as follows.

When the device is in use it is placed in any desired position and the cooling element 9 is preferably in a horizontal position. The refrigerant is then run through the cooling element, which cools it to a very low temperature. Any suitable material it is desired to freeze may be placed directly on top of the cooling element, such, for example, as the ice cube trays, and ice will be very quickly formed. It will be seen that by this means the ice cube trays or whatever is placed on the cooling element, are all in view and their condition easily seen and any one of them can be easily and quickly removed. They can be seen through the glass door and they can be seen when the door is open, whether it is made of glass or opaque material.

The air surrounding the cooling element is cooled and drops by gravity down into the chamber 28. This cold air displaces the warmer air and causes it to rise up and pass over the partition made up of the members 25 and 26. The very cold air remains in the chamber 28 and it is only the warmer air which passes over the top of the partition into the chamber 29. By suitably regulating the height and horizontal position of the partition, the relative temperature in the two chambers may be greatly varied.

The chamber 28 may be used for materials it is desired to freeze, such as meats, butter, ice cream and any edible material which is not injured by freezing. Edibles, such as vegetables, salads,

milk, eggs and any other material which it is desired to keep cold, but which should not be frozen, may be placed in chamber 29. The temperature in the chamber 29 may be varied to secure the desired temperature by adjusting the partition to secure this result.

When it is desired to defrost the device, it is only necessary to scrape the frost from the smooth sides of the cooling element. To make it easy to do this, the cooling element may be moved up out of the receptacle by simply sliding the part 10a up to the top of the slot 10b. The dotted position of the cooling element in Fig. 4 shows the cooling element partially moved up, but it can be moved up so that it is entirely outside of the receptacle. Instead of scraping the frost off of the cooling element, it can be easily and quickly defrosted by simply moving the member 10a up to the top of the refrigerating receptacle and moving the cooling element about its pivot to a vertical position. In this position the entire cooling element is outside of the refrigerating receptacle and is in the warm air. The frost will quickly and easily melt, so that the cooling element will be free from frost or ice. The water due to this melting may be caught in a suitable receptacle, either at the bottom of the refrigerating receptacle or at the top of the refrigerating receptacle just below the cooling element. It will be seen that this device can be defrosted by scraping off the frost or ice from the cooling element, or by permitting it to melt, without reducing the temperature of the refrigerating receptacle and without removing any of the material therein, for when the doors are open to move the cooling element up out of the receptacle, the cold air will be held in by gravity and cannot pass out and the warm air cannot pass in because it is too light, the colder air in the refrigerating receptacle preventing this.

When it is desired to maintain one or both of the chambers 28 and 29 at any predetermined temperature, any suitable automatic shut off device for shutting off the supply of refrigerant may be used and may be set at the desired temperature to shut off the refrigerant to secure this result.

In all of these constructions the conduits connecting the cooling element with the source of refrigerant supply are flexible and of proper length to permit the cooling element to be moved up out of the refrigerating receptacle for defrosting or other purposes. The essential thing in this construction so far as defrosting is concerned, is that there shall be means for isolating the cooling element from the air within the refrigerating receptacle while it is still connected to the source of refrigerant supply and surrounding the cooling element by outside air, and for reassociating the cooling element with air inside the receptacle to cool such air.

I claim:

1. A refrigerating apparatus comprising a refrigerating receptacle closed at the bottom, ends and sides, a cooling element in said refrigerating receptacle, located near the top thereof and extending part way across said receptacle, and a partition which divides the receptacle into two chambers of unequal temperatures, said partition extending from the bottom of the receptacle upwardly, with its upper edge below the cooling element, the air around the cooling element being cooled thereby and dropping by gravity into the chamber below the cooling element and causing the warmer air to rise and pass over the top

of the partition into the other chamber, so that two connected chambers are provided, cooled to different temperatures by the same cooling element.

2. A refrigerating apparatus comprising a refrigerating receptacle closed at the bottom, ends and sides, a cooling element in said refrigerating receptacle, located near the top thereof and extending part way across said receptacle, a partition which divides the receptacle into two chambers, said partition extending from the bottom of the receptacle upwardly, with its upper edge below the cooling element, the air around the cooling element being cooled thereby and dropping by gravity into the chamber below the cooling element and causing the warmer air to rise and pass over the top of the partition into the other chamber, so that two connected chambers are provided, cooled to different temperatures by the same cooling element, and means for adjusting the height of said partition to vary the relative temperatures of the two connected chambers.

3. A refrigerating apparatus comprising a refrigerating receptacle closed at the bottom, ends and sides, a cooling element in said refrigerating receptacle, located near the top thereof and extending part way across said receptacle, a partition which divides the receptacle into two chambers of unequal temperatures, said partition extending from the bottom of the receptacle upwardly, with its upper edge below the cooling element, the air around the cooling element being cooled thereby and dropping by gravity into the chamber below the cooling element and causing the warmer air to rise and pass over the top of the partition into the other chamber, so that two connected chambers are provided, cooled to different temperatures by the same cooling element, and means for varying the relative sizes of said chambers to vary the relative temperatures therein.

4. A refrigerating apparatus comprising a refrigerating receptacle closed at the bottom, ends and sides and having a flat top, a cooling element in said refrigerating receptacle, located near the top thereof and extending part way across said receptacle, a partition which divides the receptacle into two chambers of unequal temperatures, said partition extending from the bottom of the receptacle upwardly, with its upper edge below the cooling element, the air around the cooling element being cooled thereby and dropping by gravity into the chamber below the cooling element and causing the warmer air to rise and pass over the top of the partition into

the other chamber, so that two connected chambers are provided, cooled to different temperatures by the same cooling element, and a door for covering the top of said refrigerating receptacle, said door when closed converting the refrigerating receptacle into a table, whereby the refrigerating apparatus performs the function of two pieces of furniture, a refrigerator and a table.

5. A refrigerating apparatus comprising a refrigerating receptacle closed at the bottom, ends and sides, a cooling element in said refrigerating receptacle, located near the top thereof and extending part way across said receptacle, a partition which divides the receptacle into two chambers of unequal temperatures, said partition extending from the bottom of the receptacle upwardly, with its upper edge below the cooling element, the air around the cooling element being cooled thereby and dropping by gravity into the chamber below the cooling element and causing the warmer air to rise and pass over the top of the partition into the other chamber, so that two connected chambers are provided, cooled to different temperatures by the same cooling element, a door for covering the top of said refrigerating receptacle, said door when closed converting the refrigerating receptacle into a table, said door forming a portion of the top of the table, and hinged extensions in alignment with said top to extend the table top and which may be moved down along the sides of the receptacle when desired.

6. A refrigerating apparatus comprising a refrigerating receptacle closed at the bottom, ends, sides and top, a cooling element in said receptacle, located near the top thereof and extending part way across said receptacle, a partition which divides the receptacle into two chambers, said partition extending from the bottom of the receptacle upwardly, with its upper edge below the cooling element, the air around the cooling element being cooled thereby and dropping by gravity into the chamber below the cooling element and causing the warmer air to rise and pass over the top of the partition into the other chamber, so as to provide two connecting chambers cooled by the same cooling element, one chamber being at a higher temperature than the other chamber, and a door in the side of the receptacle, opening into one of said chambers, so that materials may be taken from said chamber without permitting the cold air to escape from the other chamber.
